Term of patent 14 years

(Cl. D87—5)

FIG. 1.

FIG. 2.

FIG. 3.

FIG. 4.

Fig. 1 is a front perspective view of a luggage case embodying our new design;

Fig. 2 is an end perspective view, on a smaller scale of the luggage case of Fig. 1;

Fig. 3 is a side elevation of the luggage case of Fig. 1, with the handle, shown in dotted lines in Fig. 1 for purposes of illustration, omitted; and

Fig. 4 is an end elevation of the luggage case as shown in Fig. 3.

The characteristic feature of our new design resides in a groove extending longitudinally around the periphery of the luggage case, flanked on each side by a pair of spaced beads disposed in generally parallel relation to the groove and separated by a recessed land.

We claim:

The ornamental design for a luggage case, as shown and described.
